UNITED STATES PATENT OFFICE.

ANDREW HOLMES, OF ATTLEBORO, MASSACHUSETTS, ASSIGNOR TO O. W. HAWKINS AND COMPANY, OF SAME PLACE.

DESIGN FOR A MEMBER FOR BELT-BUCKLES.

SPECIFICATION forming part of Design No. 34,265, dated March 26, 1901.

Application filed February 14, 1901. Serial No. 47,378. Term of patent 3½ years.

To all whom it may concern:

Be it known that I, ANDREW HOLMES, a resident of Attleboro, in the county of Bristol and State of Massachusetts, have invented and produced a certain new and useful Design for a Member for a Belt-Buckle; and I do hereby declare that the following is a full, clear, and exact description thereof, reference being had to the accompanying drawings, and to the letters of reference marked thereon, which form a part of this specification.

Figure 1 represents a back elevation of my design for a member for a belt-buckle. Fig. 2 represents a view of the lower edge of the same. Fig. 3 is a perspective view of the member of a belt-buckle.

As shown in the drawings, the material features of my design consist of a plate A, having its two side lines e d converging upward toward each other at about an angle of sixty degrees, and the top and bottom c r of one half of the plate are at right angles to one of the side lines d, and the top and bottom lines of the other half of the plate are made at right angles to the outer side e of that half of the plate, and the upper and lower ends are turned outwardly to form ears g g, having small openings h made in them. A vertical oblong opening k is made in the plate near the middle of the left-hand half of the plate parallel with the side d.

Having thus described my invention, I claim as new and desire to secure by Letters Patent—

The design for a member for a belt-buckle as herein shown and described.

In witness whereof I have hereunto set my hand, this 13th day of February, 1901, at Providence, in the county of Providence and State of Rhode Island.

ANDREW HOLMES.

In presence of—

HOWARD E. BARLOW,
EDGAR S. MARSH.
